CLAIM

I claim the ornamental design for a measuring cup, as shown and described.

DESCRIPTION

FIG. 1 is a top perspective view of a measuring cup showing my new design;

FIG. 2 is a left side elevational view thereof;

FIG. 3 is a front elevational view thereof; the rear elevational view being an identical mirror image thereof;

FIG. 4 is a right side elevational view thereof;

FIG. 5 is a top plan view thereof; and,

FIG. 6 is a bottom plan view thereof.

The broken lines and area within in FIG. 6 represents portions of the measuring cup that form no part of the claimed design.
